(57) **CLAIM**

The ornamental design for a buckle assembly, as shown and described.

DESCRIPTION

FIG. 1 is a bottom-front perspective view of a buckle assembly showing my new design;

FIG. 2 is a top view thereof;

FIG. 3 is a front view thereof;

FIG. 4 is a left side view thereof;

FIG. 5 is a right side view thereof;

FIG. 6 is a bottom view thereof;

FIG. 7 is a rear view thereof;

FIG. 8 is a top-right-front perspective view of a right side portion of the buckle assembly showing my new design;

FIG. 9 is a front view thereof;

FIG. 10 is a top view thereof;

FIG. 11 is a left side view thereof;

FIG. 12 is a right side view thereof;

FIG. 13 is a bottom view thereof;

FIG. 14 is a rear view thereof;

FIG. 15 is a bottom-front perspective view of a left-side portion buckle assembly showing my new design;

FIG. 16 is a front view thereof;

FIG. 17 is a top view thereof;

FIG. 18 is a right side view thereof;

FIG. 19 is a left side view thereof;

FIG. 20 is a bottom view thereof; and,

FIG. 21 is a rear view thereof.

The broken lines in the views indicate features of the buckle assembly that form no part of the claimed design.

1 Claim, 21 Drawing Sheets
